UNITED STATES PATENT OFFICE.

EDWARD F. WHITE, OF WEYMOUTH, ASSIGNOR TO JAMES W. BROOKS,
TRUSTEE, OF CAMBRIDGE, MASSACHUSETTS.

MACHINE FOR PRICKING, TRIMMING, AND CHANNELING SOLES.

SPECIFICATION forming part of Letters Patent No. 249,279, dated November 8, 1881.

Application filed May 2, 1881. (No model.)

To all whom it may concern:

Be it known that I, EDWARD F. WHITE, of Weymouth, county of Norfolk, and State of Massachusetts, have invented a new and useful Improvement in Machines for Pricking, Trimming, and Channeling Soles, of which the following description, in connection with the accompanying drawings, is a specification.

This invention is an improvement upon United States Patent to J. S. Turner, No. 215,547, for pricking and trimming soles.

The object of my invention is to channel the sole just before it is pricked, thus avoiding the now common plan of marking the outer sole and then channeling it by hand—two operations—before applying the sole to the machine to be pricked, or pricked and trimmed, as in the said Turner patent.

In this my invention I have made one of the under supports or rests substantially such as shown in the said patent, movable horizontally toward and from the other under support or rest, and I have also adapted the presser, placed above and co-operating with the movable rest, to slide horizontally with the said rest when the sole is clamped between them, they, in connection with the awl, which will then preferably rest in the work, carrying or feeding the sole forward against a stationary channel-cutter, the upper end of which is extended upward into and just above the top of the movable rest, the forward movement of the sole of the lasted shoe against this cutter forming a channel in the sole a little in advance of the awls, the line of the channel being defined by the outline of the last having the upper of the lasted shoe upon it, as the line of pricking and trimming is determined in the said Turner patent. The lip of the channel turned over in advance of the operation of the awl is kept out of the way of the awl by means of a channel-opener at the side of the rearmost under support or rest. The presser-foot above the rearmost rest is thrown down upon the material to clamp and hold it firmly while the awl and the forward presser-foot and under support or rest move backward after having fed the material forward.

In this application I have considered it nec-

essary to show only such parts of the Turner machine as are required to illustrate my invention, and I have designated by same letters those parts which are common to both machines.

My invention consists in a machine of the class herein shown and specified for pricking and trimming soles when provided with a channel-cutter; also, in details of construction, as will be hereinafter described, and pointed out in the claims.

Figure 1 represents a front-side elevation of a sufficient portion of a sole pricking and trimming machine to illustrate my invention, the right-hand end of the machine being mostly broken away to clearly show the lever and cam on the main shaft, which operate to raise and lower that one of the presser-feet located above the rearmost under support or rest; Fig. 2, a front-end view thereof, both presser-feet being lifted and the movable rest being moved forward; Fig. 3, a top view of the under supports or rests, with the movable rest forward, the upper end of the channel-cutter being shown in the slot of the said rest; Fig. 4, details of the channel-cutter; Fig. 5, details of the channel-opener; Fig. 6, a top view and section of a piece of sole-leather cut, pricked, and channeled, as it will be by my improved machine; and Fig. 7 shows the awls and cutters and their carriers detached from the machine.

The sliding carriage d' , having two uprights, d^2 , to receive the pin 8 for the carriers $d^3 d^4$, provided with the two awls 10 and the two chisels or cutters 11 and the sliding cam bar or slide d^5 , are as in the said patent. Upon this carriage d' , by the screws 20, I have secured an arm, A, the forward end of which I have attached by a screw, 21, to an auxiliary carriage, B, fitted between suitable guides, 22, the said auxiliary carriage having secured to it the movable rest C, which takes the place of the rest e, shown in the said patent.

In the Turner patent the two presser-feet had only a rising-and-falling movement, and were raised and lowered simultaneously, both being actuated by the lever f^4 and link f^3 therein, made double or forked; but in this

my machine the presser-foot D, which takes the place of the presser-foot f of the said patent, is pivoted at i upon the upright E, secured to the carriage d', so that the said presser-foot, besides its rising-and-falling movement, is moved horizontally backward and forward in unison with the rest C, awls 10, and cutters 11. The arm D' of this presser-foot is connected, by link f³, with lever f⁴, corresponding with a like lever in the Turner patent.

The presser-foot f', like that shown in the Turner patent, and having like movements, is actuated by means of a link, F, and the lever F', the rear of which is moved at the proper time by the cam F² on the main shaft b.

The rearmost under support or rest, e', for the sole of the lasted boot or shoe to be channeled, pricked, and trimmed (substantially such a rest as that in the Turner patent) is secured on a block, B², in line with the auxiliary carriage B, and upon the side of this rest I have secured by screw 24 the channel-opener G.

The forward longitudinally-movable rest, C, before referred to, is provided with a slot, 25, in which is placed the channel-cutter H, the upper end of which is beveled and sharpened, as shown in Fig. 4, the upper end of the said channel-cutter, extended above the rest C, cutting a channel, C², into the leather or sole h at its under side immediately in advance of the awl 10. To cut the channel, the sole h is clamped firmly at bottom and top between the rest C and presser D, and is carried forward against the sharp end of this channel-cutter, a portion of the leather being lifted and turned over to form a channel flap or lip, 28. The parts of the rest C each side of the slot 25 so support the sole as to insure a uniform depth of channel; but this channel-cutter may be adjusted vertically by the screws 26, to insure a channel of greater or less depth.

The lip 28 of the channel, after passing the awls, is held open by means of the channel-opener G. This channel-opener also prevents the liability of the awl pricking, and thereby injuring the lip which is to cover the stitches in the sole after they have been formed by hand.

To stitch "aloft," as it is called in shoe-factories, I may employ a channel-opener shaped to remove the leather and form a groove without a lip.

The awls and cutters operate just as in the Turner patent, the former to prick the series of holes h² through the sole h in the channel,

and the cutters to cut the leather and give shape to the sole by removing the surplus leather, as at x.

The springs g g', acting on the carriers d² d³, keep the rollers at their rear ends against the cam-shaped ends of the bar d⁵. Instead of operating these carriers as herein shown and as in the Turner patent, I may operate them as in a machine devised by C. W. Gledden.

The upper of the boot or shoe just outside of and resting against the last, as in the Turner patent referred to, will be held pressed against the front sides or faces of the pressers D and f', and the channel and line of awl-holes in the sole and the edge of the sole as formed by the cutters 11 will all be defined from the shape of the last for the purposes fully described in the Turner patent.

I do not desire to limit my invention to the exact construction of channel-cutter herein described.

I claim—

1. In a machine to prick and trim a piece of leather applied to a lasted boot or shoe to form a sole therefor, a channel-cutter to cut a channel in the said leather, combined with an awl to perforate the said leather through and through from the bottom of the said channel, and a cutter to trim the said leather outside the perforated and channeled portion substantially parallel with the direction of the said perforations and give to it proper shape for the sole of the lasted boot or shoe, substantially as described.

2. The rest e', and presser f', and the horizontally-movable rest C, and presser D, combined with a channel-cutter co-operating therewith, substantially as described.

3. The stationary channel-cutter extended up through a slot in the horizontally-movable rest, and the horizontally-movable lifting-presser D, shaped to bear upon the welt of the shoe and act against the upper on the last near the welt, to guide the shoe to insure the formation of a channel to correspond in shape to the outline of the bottom of the last or inner sole thereon, substantially as described.

In testimony whereof I have signed my name to this specification in the presence of two subscribing witnesses.

EDWARD F. WHITE.
